UNITED STATES PATENT OFFICE.

JOHN B. MOFFAT, OF YONKERS, NEW YORK, AND WILLIAM F. BROWN, OF NEWARK, NEW JERSEY, ASSIGNEES TO THE BIGELOW CARPET COMPANY, OF MASSACHUSETTS.

DESIGN FOR CARPET.

SPECIFICATION forming part of Design No. 27,411, dated July 20, 1897.

Application filed June 7, 1897. Serial No. 639,764. Term of patent 3½ years.

To all whom it may concern:

Be it known that we, JOHN B. MOFFAT, a citizen of the United States, and a resident of Yonkers, county of Westchester, and State of New York, and WILLIAM F. BROWN, a subject of the Queen of Great Britain, residing at Newark, county of Essex, State of New Jersey, have invented a new and original Design for Carpets and Borders, of which the following is a specification.

This invention comprises two parts—namely, the design A for a carpet and the design B for a border; and we do hereby declare that the drawing accompanying this specification conveys to any one a clear understanding of the same and is sufficient to enable such person to use our invention.

The design A is characterized by large clusters of leaf and flower forms.

The design B is characterized by a panel of large clusters of leaf and flower forms.

What we claim, and desire to secure by Letters Patent, is—

1. In a design for a carpet, the body A, substantially as shown. 25
2. In a design for a carpet, the border B, substantially as shown.
3. The design for a carpet comprising the body A and the border B, substantially as shown. 30

In testimony whereof we have signed our names to this specification in the presence of two subscribing witnesses.

JOHN B. MOFFAT.
W. F. BROWN.
